UNITED STATES PATENT OFFICE.

HENRY COLLIER SMITH AND OLLIE L. BOTKIN, OF ST. MARYS, OHIO, ASSIGNORS TO
THE QUICKWORK COMPANY, OF ST. MARYS, OHIO.

INDICATOR FOR SHEARS.

Application filed May 26, 1924. Serial No. 715,907.

To all whom it may concern:

Be it known that we, HENRY COLLIER SMITH and OLLIE L. BOTKIN, citizens of the United States, and residents of St. Marys, 5 Auglaize County, Ohio, have invented a new and Improved Indicator for Shears, of which the following is a specification.

This invention relates to means for indicating the direction in which a sheet of metal must be swung in order to be operated upon along a predetermined line by means of machine tools, the invention being for the same purpose as the indicating device shown in Patent No. 1,313,960, dated August 26, 15 1919; and the object of this invention is to provide a simple and effective indicator which is visible from any side of the tool convenient to the workmen.

This invention consists of a rotary indicator mounted on a vertical shaft, a pointer adapted to be moved to follow the predetermined line of shear, and connecting mechanism between the pointer and indicator whereby the indicator will move 25 with the pointer.

It further consists in the details of construction illustrated in the accompanying drawings and particularly pointed out in the claims.

30 In the drawings, Fig. 1 is an elevation of a shear equipped with rotary cutters and with our improved indicating mechanism, Figs. 2 and 3 are sections on the lines 2—2 and 3—3 respectively of Fig. 1. Fig. 4 is a plan of the indicating mechanism. Fig. 5 is a section on the line 5—5 of Fig. 4.

Similar reference characters refer to like parts throughout the several views.

40 Rotary cutters are used to cut metal plates of any desired size along straight and curved lines. Unlike reciprocating shears where the work is held stationary during the cutting operation, the work must be fed to the rotary cutters and this is mostly done by hand.

As the workmen who handle these plates are usually unable to see the line on which the plates are to be cut and therefore cannot know in which directions to swing the 50 plates to cause the cutters to follow the predetermined lines, means must be provided to indicate to the workmen the direction and comparative distance the plates must be swung, no matter on which side of the machine the workmen are stationed.

The indicator is preferably mounted at the front of the machine so it can be seen from the front and both sides. We prefer to secure a cylindrical bracket 1 to the front 2 of the shear and mount a shaft 3 in the bushing 4 in this bracket 1. A cylindrical drum 5 is secured to the upper end of this shaft which is supported by this drum, while a pinion 6 is formed on or secured to the lower end of this shaft. A guide frame 7 and its follower plate 8 are journaled on this shaft, being positioned by the pinion, and slidably support a rack-bar 9 which is held in mesh with the pinion by the gib 10 and screws 11.

55 A shaft 13 is mounted in the bearing 14 secured to the side of the frame 15 of the shear, and has a crank 16 attached to its upper end. A pin 17 at the outer end of this arm connects to the rack-bar 9 so that the indicator drum 5 will turn with the shaft 13. The lower end of the shaft is journaled in the bearings 18 on the bracket 19 secured to the frame 15, and the gear 20 and arm 21 are attached to this shaft. This 60 arm has an upturned end 23 which is adjacent a rest bar 24 for the hand of the operator who grasps the end 23 of the arm 21 to swing them together with the shaft 13.

The bracket 19 also carries two bearings 26 for the rotatable and slidable cylindrical rack-bar 27 whose teeth 28 mesh with the gear 20 on the vertical shaft 13. This bar 27 has a collar 29 secured to one end and this collar carries an inclined pointer 30 which is adjustable therein and slides along on the plate 31 which is being passed between the rotary cutters 32 and 33.

65 These cutters are shown separated to receive the plate 31. When the shear is in operation, the point of the inclined pointer slides on the plate being sheared, being moved in and out to follow the shear line by the operator swinging the arm 21 and turning the gear 20 and shaft 13. When the pointer is moved out, (to the left in Fig. 1) the shaft 13 turns with it and moves the rack bar 9 to the left. This carries the indicating line 34 on the drum 5 to the left of the line 35 on the bracket 1 and shows that the plate must be swung to the right to carry the line of shear to the operating line of the rotary cutters. This is true no matter where the workmen are located, the plate always being moved to bring the 70 100 105 110

marks 34 and 35 into alinement, no matter how curved or how straight the line of shear may be. The collar 29 is adjustable on the bar 27 so that the pointer 30 may be correctly located with reference to the cutters.

As the pointer 30 can be adjusted in the collar 29, the distance between its point and the cutters can be varied as may be found necessary, and it may be said that for straight line cutting or for curves of large radii, this distance may be greater than when the line of shear has sharper curves. But regulation is easier when this distance is greater.

It is evident that this indicator is not limited to machines embodying rotary cutters but may be employed on different types of machine tools wherein the work is operated upon along predetermined lines.

The details of construction and the proportions of the parts may all be changed by those skilled in the art without departing from the spirit of our invention as set forth in the following claims.

We claim:—

1. In combination with a machine tool adapted to operate along a predetermined line on material passing the tool, a pointer shiftable transversely of said line, a shaft and means connecting the same to said pointer whereby the shaft is caused to rotate in proportion to the transverse movement of the pointer, a rotatable indicator, and means connected to the shaft to turn the indicator.

2. In combination with a machine tool adapted to operate along a predetermined line on material passing the tool, a pointer, a rotatable and slidable shaft to which said pointer is adjustably attached, a vertical shaft, means connecting said shafts whereby the vertical shaft rotates as the slidable shaft moves endwise, a rotatable indicator, and means connected to the vertical shaft to turn the indicator.

3. In combination with a machine tool adapted to operate on moving material, means for indicating angular displacement of the material with reference to the tool comprising a drum rotatable on a vertical axis and visible to workmen on both sides and in front of the machine tool, and manually operable means connected to the drum and embodying a pointer adapted to be moved relative to the work to follow the desired line of the operation of the tool.

4. In combination with a machine tool adapted to operate on moving material, a rotatable drum mounted on a vertical axis and adapted to turn to indicate angular displacements of the material with reference

to the tool, and be visible from the front and both sides of the tool, a shaft rotatable with said drum, means to rotate the shaft, a pointer, a support therefor, and means connecting said support to said shaft whereby the pointer may be caused to move in proportion to the angular displacement of the work.

5. In combination with a machine tool comprising a pair of rotary cutters adapted to operate on metal plates along predetermined lines marked on the plates, a slidable and rotatable shaft, a pointer carried by the shaft adapted to be moved to follow said line and be carried in and out by said shaft as said plates are displaced angularly with reference to the cutters, a rotatable indicating drum visible from the sides and front of the machine tool, a second shaft, means connecting said second shaft and drum so they will turn together, and means to connect said shafts so that as one slides in and out the other will turn and turn the drum.

6. In combination with a machine tool comprising a pair of rotary cutters adapted to operate on metal plates along predetermined lines marked on the plates, a slidable and rotatable shaft, a pointer carried by the shaft adapted to be moved to follow said line and be carried in and out by said shaft as said plates are displaced angularly with reference to the cutters, a rotatable indicating drum visible from the sides and front of the machine tool, a second shaft, means connecting said second shaft and drum so they will turn together, and means to connect said shafts so that as one slides in and out the other will turn and turn the drum, said connection embodying circumferential teeth on the slidable shaft and a pinion on said second shaft.

7. In combination with a machine tool comprising a pair of rotary cutters adapted to operate on metal plates along predetermined lines marked on the plates, a slidable and rotatable shaft, a pointer carried by the shaft adapted to be moved to follow said line and be carried in and out by said shaft as said plates are displaced angularly with reference to the cutters, a rotatable indicating drum visible from the sides and front of the machine tool, a second shaft, means connecting said second shaft and drum so they will turn together, means to connect said shafts so that as one slides in and out the other will turn and turn the drum, and an arm attached to said second shaft to turn it and the drum and to slide the first shaft so as to cause the pointer to follow the lines on the plates.

HENRY COLLIER SMITH.
OLLIE L. BOTKIN.
